ANTIRATTLE DOVETAIL FOR DOORS

Thomas T. Logie, Bridgeport, and Arthur Claud-
Mantle, Trumbull, Conn., assignors to The Bas-
sick Company, Bridgeport, Conn., a corpora-
tion of Connecticut

Application March 21, 1935, Serial No. 12,170

5 Claims. (Cl. 16—85)

The present invention relates to improvements in self-adjusting anti-rattle dovetails particularly for automobile doors, and of the type in which a pair of laterally adjustable resiliently supported dove-tail block members are adapted to have a wedge member engaged between them, the respective block members being supported against vertical movement, whereby the rattle usually resulting from vibration and weaving of the door is prevented and the door is effectually retained against vertical movement, while at the same time lateral movement and wear is compensated for.

It is an object of the present invention to provide improved means for slidably retaining the block members in the casing, whereby accidental displacement is prevented, and at the same time assembly, and removal of the blocks for replacement purposes, is facilitated. Another object is to provide block members which will more accurately fit in the casing, and to this end we propose to provide means for compensating for slight variations in the dimensions of casing. A further object is to provide a block member formed of sheet metal, and which will be of hollow formation opened at the back to provide a socket for receiving and retaining the end of the pressure spring.

With the above and other objects in view an embodiment of the invention is shown in the accompanying drawing, and this embodiment will be hereinafter more fully described with reference thereto, and the invention will be finally pointed out in the claims.

35 In the drawing:

Fig. 1 is a front elevation of the socket member, according to the exemplary illustrated embodiment of the invention, showing in dot-and-dash lines the engagement of the wedge member with the blocks.

40 Fig. 2 is an end elevation thereof.

Fig. 3 is a front elevation of the wedge member.

Fig. 4 is a front elevation of the socket member, with the face plate removed, one of the block members being shown in dot-and-dash lines in its fully retracted position.

45 Fig. 5 is a front elevation thereof.

Fig. 6 is a sectional view taken on line 6—6 of Fig. 1.

50 Fig. 7 is a perspective view of one of the block members looking toward its forward end.

Fig. 8 is a perspective view of one of the block members looking toward its rearward end.

55 Similar reference characters indicate corre-

sponding parts throughout the several figures of the drawing.

Referring to the drawing the anti-rattle dovetail device, according to the exemplary illustrated embodiment of our invention, comprises generally a socket member, adapted to be secured to the door frame within a suitable recess, and a wedge member, adapted to be secured to the edge of the door in relation to enter the socket member upon closing of the door.

The casing of the socket member comprises an outer part consisting of a face plate member 10, preferably formed of sheet metal, having a flange 11 at its forward edge bent at a right angle, and a lip 12 bent forwardly from the flange 11. A 15 rearwardly converging opening 13 is provided in the face plate and extends across the flange 11 to the lip 12, the forward portion of the opening having its upper and lower edges disposed in parallel relation. Counter sunk screw holes 14 20 are provided in the face plate near the upper and lower edges for attachment of a socket member by screws to the door frame.

The inner or box part of the socket member is also formed of sheet metal, and, as shown in Figs. 4 and 5, comprises a rectangular portion 15 25 having side wall flanges 16—16 bent from its upper and lower edges and a rear wall flange 17 bent from its rear edge. The flanges 16—16 have attaching ears 18—18 bent outwardly therefrom, 30 and which are adapted to be secured to the face plate by spot-welding or other suitable means.

A pair of inwardly bent lugs 19—19 are struck from the rear wall flange 17 for supporting the ends of the pressure springs, as will hereinafter more fully appear, and upon the forward edges of the side wall flanges 16—16 there are provided projecting lugs 20—20, narrower than the side flanges and disposed intermediate their upper and lower edges, these lugs being bent rearwardly into spaced and parallel relation with the inner surfaces of the side walls.

A forwardly projecting lip 21 is provided at the forward edge of the portion 15 and is curved slightly to bring its edge into alignment with the 45 lip 12 and to provide a guide surface for the wedge, as will hereinafter more fully appear.

A pair of opposed block members are provided in the casing, these being of sheet metal, pressed and bent to shape. They each comprise an inclined slightly arcuate face portion 22, side wall portions 23—23 bent from the side edges of the face portion in spaced and parallel relation to each other, a front wall portion 24 bent from the forward edge of the face portion in abutting rela-

tion to the forward edges of the side wall portions, and a base wall portion 25 bent rearwardly from the front wall portion 24 about the rounded forward corner edges 26-26 of the side wall portions against the base edges of said side wall portions. An inwardly bent lug 27 is struck from the base portion 25 to form an abutment for the end of the pressure spring, presently to be more fully referred to. An aperture 28 for receiving the lug 20 is provided in the front wall portion 24, its lower edge being cut into the base portion 25.

In the assembled relation of the blocks in the socket member the lugs 20-20 are engaged in the apertures 28-28 of the blocks, the surfaces 25-25 being in parallel relation to each other and in sliding engagement with the side walls 16-16. The blocks contact each other at their inner wide ends. The pressure springs 29-29 are engaged at one end upon the lugs 19-19 and press against the rear wall 17, and at their other ends are engaged in the blocks and press against the lugs 27-27, to force the blocks forwardly against the lugs 20-20.

The wedge member comprises an attaching base 30 having screw holes 31, for attachment by screws to the door, and a rigid projecting wedge-shaped projection 32 having flat inclined sides 33, substantially corresponding to the inclination of the dovetail blocks.

The slightly arcuate shape of the inclined surfaces of the blocks permits firm engagement of the wedge member irrespective of slight variations in the vertical alignment of the door. Obviously this arrangement may be reversed, if desired, and the inclined surfaces of the wedge member made slightly arcuate, the inclined surfaces of the blocks being flat.

The operation is as follows:—

When the door is in open position the blocks are projected forwardly against the lugs 20-20 as indicated in Figs. 1 and 4. As the door is closed the wedge member 32 engages between the blocks, contacting therewith before the door is completely closed, the complete closure of the door causing the blocks to be moved laterally of the casing against the pressure of the springs, which hold the blocks snugly against the wedge member, while the inclination of the engaging surfaces is such that vertical pressure will not displace the blocks and cause vibration.

The length of the blocks is such that in their normal partially retracted position when engaged by the wedge member, as shown in dot-and-dash lines in Fig. 1, the lugs 20-20 remain in retaining engagement with the apertures 28-28 to retain the blocks against vertical displacement. In the fully retracted position of the blocks—as one of the blocks is shown in dot-and-dash lines in Fig. 4, and to which position it may be pressed by a suitable tool or by hand—the front wall 24 is clear of the lug 20 and may, by tilting its forward end away from the side wall 16 out of the path of the lug 20, be readily removed. The assembly is accomplished in the same way, one block being assembled after the other. The construction is such that the possibility of accidental displacement of the blocks is entirely prevented, either when in use, or before assembly of the box part of the socket member 70 with the face plate. Also the engagement of the lugs 20 with the blocks in the normal retracted position insures proper positioning of the blocks while engaged by the wedge member.

The arrangement of the base portion 25 of the sheet metal block members is such that this por-

tion may be sprung away from the edges of the side 23-23, if desired, so as to compensate for any irregularity in the dimension between the side flanges 16-16.

The door is provided with the usual latch not shown, which engages behind a striker on the door frame, and the present device is such that it permits the door to close sufficiently to allow the latch to operate, and thereupon exerts an outward pressure on the door to force the latch bolt 10 tightly against the striker. Upon release of the latch the device exerts an opening pressure on the door.

Should the wedge member be out of alignment with the socket, due to sagging of the door or inaccurate mounting of the wedge member, the independent movement of the respective blocks will permit them to adjust themselves to the wedge surfaces and perform their cooperative retaining function.

While we have shown the socket member on the door frame and the wedge member on the door, it will be obvious that this arrangement may be reversed, if desired.

We have illustrated and described preferred and satisfactory embodiments of the invention, but it will be obvious that changes may be made therein, within the spirit and scope thereof, as defined in the appended claims.

Having thus described our invention what we claim and desire to secure by Letters Patent is:—

1. A socket member, for use in an anti-rattle device for doors, in which a tapered wedge member is adapted to be engaged with said socket member, comprising a casing, a pair of block members mounted in said casing for sliding movement therein, each of said block members being formed of sheet metal and including an inclined face portion, side wall portions extending from the side edges of said face portion, a front wall portion extending from the forward edge of said face portion, and a base portion extending rearwardly from said front portion, each of said block members being hollow and open at its inner rearward end, a pair of helical springs acting between said casing and said block members and engaged in said block members through said inner open ends and urging said block members forwardly in said casing, and means for limiting the forward movement of said block members.

2. A socket member, for use in an anti-rattle device for doors, in which a tapered wedge member is adapted to be engaged with said socket member, comprising a casing, a pair of block members mounted in said casing for sliding movement therein, each of said block members being formed of sheet metal and including an inclined face portion, side wall portions extending from the side edges of said face portion, a front wall portion extending from the forward edge of said face portion and abutting the forward edges of said side wall portions, and a base portion extending rearwardly from said front portion and abutting the base edges of said side wall portions, each of said block members being hollow and open at its inner rearward end, a pair of helical springs acting between said casing and said block members and engaged in said block members through said inner open ends and urging said block members forwardly in said casing, and means for limiting the forward movement of said block members.

3. A socket member, for use in an anti-rattle device for doors, in which a tapered wedge mem-

ber is adapted to be engaged with said socket member, comprising a casing, a pair of block members mounted in said casing for sliding movement therein, each of said block members being formed of sheet metal and including an inclined face portion, side wall portions extending from the side edges of said face portion, a front wall portion extending from the forward edge of said face portion and abutting the forward edges of said side wall portions, and a base portion extending rearwardly from said front portion and abutting the base edges of said side wall portions, each of said block members being hollow and open at its inner rearward end, said base portion being adapted to be sprung away from said side portions, a pair of helical springs acting between said casing and said block members and engaged in said block members through said inner open ends and urging said block members forwardly in said casing, and means for limiting the forward movement of said block members.

4. A socket member, for use in an anti-rattle device for doors, in which a tapered wedge member is adapted to be engaged with said socket member, comprising a casing, a pair of block members mounted in said casing for sliding movement therein, each said block members being formed of sheet metal and including an inclined face portion, side wall portions extending from the side edges of said face portion, a front wall portion extending from the forward edge of said face portion, a base portion extending rearwardly from said front portion, and a lug extending inwardly from said base portion, each of said block members being hollow and open at its inner rearward end, a pair of helical springs acting between said casing and block

members and engaged in said block members through said inner open ends and abutting said lugs and urging said block members forwardly in said casing, and means for limiting the forward movement of said block members.

5. A socket member, for use in an anti-rattle device for doors, in which a tapered wedge member is adapted to be engaged with said socket member, comprising a casing having upper and lower walls, a pair of block members mounted in said casing for sliding movement therein, each of said block members being formed of sheet metal and including an inclined face portion, side wall portions extending from the side edges of said face portion, a front wall portion extending from the forward edge of said face portion and having an aperture therein, and a base portion extending rearwardly from said front portion, each of said block members being hollow and open at its inner rearward end, a pair of helical springs acting between said casing and said block members and engaged in said block members through said inner open ends and urging said block members forwardly in said casing, a pair of guide means at the forward end of said casing extending rearwardly in parallel spaced relation to said upper and lower walls and engaging said apertures in the front walls of said block members adapted to limit the forward projecting movement of said block members and to retain said block members during partial predetermined retraction, said block members adapted upon retraction beyond said partial predetermined retraction to become disengaged from said guide means to permit removal of said block members.
